(57) **CLAIM**

The ornamental design for a ornament packaging, as shown and described.

DESCRIPTION

FIG. 1 is a top view of a first embodiment of my new design, the rear view being a mirror image thereto;
FIG. 2 is a sectional view thereof, taken along lines 2-2 of FIG. 1, the opposite view being a mirror image thereof; and, FIG. 3 is a top left perspective view thereof.
The solid, wavy lines in each Figure represent the boundaries of my claimed design. The dashed lines in FIGS. 1 and 3 represent environmental elements. The dashed lines in FIG. 2 represent optional glass ornaments. All other views are not claimed.
